Patented May 8, 1917.

Inventor
Hyman Edelman,

By Charles Turner Brown
Atty.

UNITED STATES PATENT OFFICE.

HYMAN EDELMAN, OF CHICAGO, ILLINOIS.

GARMENT.

1,225,732.

Specification of Letters Patent.

Patented May 8, 1917.

Application filed August 9, 1916. Serial No. 113,906.

To all whom it may concern:

Be it known that I, HYMAN EDELMAN, a citizen of the United States, residing at Chicago, in the county of Cook and State of Illinois, have invented certain new and useful Improvements in Garments; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to garments adapted to be worn by boys and men over the trousers which are usually worn by them, and known to the trade and the public generally as overalls.

20 The objects of the invention are, to obtain a garment of the kind named which is made without side openings, and which can be as readily and easily put on and taken off as though said side openings were made 25 therein; to obtain a garment in which pockets may be placed and the openings to said pockets positioned on the sides of the garment, being located where side openings, if used, are located; and to obtain a garment 30 of the kind named which will not expose to view, when the same is in proper wearing position, the means whereby the making and using of said opening, (or aperture) is obviated.

35 In the drawing referred to Figure 1 represents the garment embodying this invention in rear elevation, with the several parts in wearing position.

Fig. 2 represents the upper end of said 40 garment in rear elevation, with the parts thereof in position to put on or take off said garment, and

Fig. 3 is a perspective, representing the upper end of said garment with the several 45 parts thereof in the position illustrated in Fig. 1.

A reference character applied to designate a given part indicates said part throughout the several figures wherever the 50 same appears.

A A' represent the legs of the garment and B, B' represent outside seams, and B'' an additional seam. b b' represent the upper ends of seams, B B' which are curved 55 inwardly to meet the waist line of the person wearing said garment. C C represent

rear pockets and D D pockets which are positioned inside of the front of the garment, having the openings (d) thereof substantially on the seams B, B. E is an aperture on the back of the garment which extends substantially the same distance above and below the waist line of the garment, (indicated by the broken line e in Fig. 1). To more particularly locate said aperture 60 it will be observed that it commences substantially on the line of the upper edges of pockets C, C, and extends to the lower ends f, f, of suspenders F, F.

It will be observed that the edge of the 70 cloth of leg A which enters into seam B'' extends in aperture E to the broken line which is lettered E', (see Figs. 1 and 3); and the edge of the cloth of leg A' which enters into said seam B'' overlaps said cloth 75 of leg A, extending to line E'', (said line E'' being a prolongation, in appearance, of seam B''). G G, represent the curved upper ends of the cloth forming the legs A, A', said cloth extending above the waist line and 80 to the ends f of the suspenders F. The stitching which is lettered J in Figs. 1, and 3, may be omitted if desired, to leave the upper end of aperture E open.

H, H, are buttons which are indicated by 85 broken lines to which the front ends of suspenders are illustrated as attached in Fig. 1, but said attachment forms no part of the invention.

To put on or take off the garment embodying this invention the front ends of the suspenders are disengaged and thrown back, to fold or bend the cloth of the back and upper ends of legs A, A, substantially on the line e (Fig. 1) as is illustrated in Fig. 2. When 90 said parts are in said last named position the aperture E is opened and the waist line of the garment enlarged to pass over the hips of the wearer in putting on or taking off the garment. When the upper end of the garment, (as illustrated in Fig. 2) is near the 95 waist line of the wearer, by putting suspenders F, over the wearer's shoulders, the aperture E is closed and the outward curves of the upper ends of seams B, B', (the parts of said seams which are designated by letters b b' in Fig. 2) are thereupon curved inwardly to the waist of the wearer, as is 100 illustrated in Figs. 1 and 3.

Some of the advantages of the inwardly 110 curved closed side seams with pocket openings in said seams, are, the button holes and

buttons which are required when the garment is provided with side openings are not required; and the falling of the flap, which exists if said buttons come off, or if the sides 5 are unbuttoned, over the openings to the pockets hindering access thereto, is done away with; it being understood that where the sides are open at the upper ends thereof the openings of the front pockets must be 10 forward of said openings. Also a good appearance is given to the garment by said closed seam.

I claim:

15 A garment made of substantially nonextensible fabric closed on the sides thereof and adapted to extend from the ankles of the wearer only to a point below the arms and provided with an aperture in the back thereof extending above and below the waist

line of the garment, a flap the ends whereof 20 extend laterally across and beyond the ends of said aperture and are attached to said back, said flap being adapted to cover said aperture and said aperture being adapted to automatically close while said garment is in 25 wearing position and to open when the upper end of the garment is turned down on the waist line thereof, to enlarge said waist line and permit said garment to be drawn over the hips of the wearer and suspender 30 straps secured to the upper edge of the back of the garment and adapted to be secured to the front of the garment.

HYMAN EDELMAN.

In the presence of—

Jos. W. SCHULMAN,

CHARLES TURNER BROWN.
